UNITED STATES PATENT OFFICE.

ROBERT HAROLD ROSENTHAL, OF NEW YORK, N. Y., ASSIGNOR TO PI LAMBDA PHI FRATERNITY, INCORPORATED, OF NEW YORK, N. Y., A CORPORATION OF NEW YORK.

DESIGN FOR A PI LAMBDA PHI FRATERNITY PIN.

Application filed April 16, 1927. Serial No. 21,624. Term of patent 14 years.

To all whom it may concern:

Be it known that I, ROBERT HAROLD ROSENTHAL, a citizen of the United States, residing at 865 Fox Street, in the county of Bronx and State of New York, have invented a new, original, and ornamental Design for the Pi Lambda Phi Fraternity Pin, of which the following is the specification, reference being had to the accompanying drawing, forming part thereof.

Figure I is a front elevation view of the Pi Lambda Phi fraternity pin showing clearly my new design.

Figure II is a bottom plan view of the pin.

I claim:

The ornamental design for a Pi Lambda Phi fraternity pin, as shown.

ROBERT HAROLD ROSENTHAL.
